UNITED STATES PATENT OFFICE.

JAMES DUNNACHIE, OF GLENBOIG STAR FIRE CLAY WORKS, COUNTY OF LANARK, SCOTLAND.

REGENERATIVE KILN FOR BURNING FIRE-BRICK, &c.

SPECIFICATION forming part of Letters Patent No. 268,771, dated December 5, 1882.

Application filed December 28, 1881. (No model.) Patented in England September 6, 1881, No. 3,562.

To all whom it may concern:

Be it known that I, JAMES DUNNACHIE, of Glenboig Star Fire Clay Works, in the county of Lanark, North Britain, have invented Improvements in Regenerative Kilns for Burning Fire-Bricks, Pottery, or other Analogous Materials, the same being applicable for other purposes, (for which I have received Letters Patent of the United Kingdom of Great Britain and Ireland, No. 3,862, dated September 6, 1881,) of which the following is a specification.

My said invention, which relates to improvements in regenerative kilns for burning fire-bricks, pottery, or other analogous materials, has for its object to more thoroughly mix the air and gas burned in such kilns, and to effect a better diffusion of the heat obtained from their combustion, as well as to more thoroughly regulate and equalize the same. These objects are effected by constructing in the walls of adjacent kilns duplex hollow spaces or flues, the alternating portions of the opposite sides of which have slits or perforations formed therein, so as to enable the heated products of combustion to be passed or discharged from the lowest part of one kiln into the lowest part of the next kiln—that is to say, the kiln which is being heated preparatory to being fired. These flue-spaces are provided with vertical or horizontal dampers, so as to shut off the communication between the kilns, the slits or perforations in the flue-spaces effecting the improved diffusion. In place of forming such flues in the walls of adjacent kilns, flues may be formed in the brick-work outside the wall, in which case the air descends down some distance below the floor of the kiln, where it passes through ports regulated by dampers into a still lower flue, from which it escapes through slits or perforations formed in the lower part of the walls into the burner or chamber or opening, wherein it mixes with the gas. For the purpose of admitting either hot air into the upper part of the kilns from an adjacent kiln or for the purpose of admitting cold air to the upper part of a kiln being fired, a similar flue—that is to say, either duplex or single—is provided with dampers and with slits or perforations in its opposite sides in the walls at or near to the upper part of the kilns.

Either hot or cold air is admitted through these upper flues and slits or perforations when the air admitted at the lower part of the kilns with the gas may be either deficient in quantity to produce complete combustion, or when the temperature of a kiln at its upper part may be either too high or too low. In place of making the flues duplex, with slits or perforations, as hereinbefore described, they may be made single, with one side—namely, that through which the discharge takes place—constructed with one, two, or more larger openings in lieu of slits or perforations above or at or level with the bottom of the kiln, and with slits or perforations at the opposite side.

The improvements hereinbefore described may also be applied to calcining-kilns and other analogous apparatus.

The accompanying drawings represent my invention as applied to kilns arranged in two opposite rows or series of five (less or more) each, the end kilns of each series being connected to the corresponding end kilns of the other series by means of flues; but it is to be understood that it may be applied to kilns otherwise arranged.

Figure 1 is a general plan of the series of kilns. Fig. 2 is an end elevation of the same. Fig. 3 is a front elevation of one of the series or rows. Fig. 4 is a longitudinal vertical section of the same. Fig. 5 is a plan of the same, partly in section, on the line 1 2, Fig. 4. The following figures are drawn to a larger scale, the better to exhibit the flues and passages: Fig. 6 is a longitudinal vertical section of a kiln of the series with portions of the adjacent kilns on either side. Fig. 7 shows one-half of a horizontal section of the same, taken on the lines 3 4, Fig. 6. Fig. 8 is a vertical transverse section on the line 5 6, Fig. 6, showing the side wall of the kiln, indicated by the arrow 7. Fig. 9 is a section on the line 5 8, Fig. 6, but showing the other side wall of the kiln, indicated by the arrow 9. Figs. 10, 11, 12, and 13 are views of a modification, hereinafter more particularly referred to.

The gas to be employed for the burning process is obtained from any convenient source. For example, it is produced in gas-producers, (indicated at A, Fig. 1,) and is led therefrom by

the main passage *a*, wherefrom lead branch passages *a'* for the gas to each kiln, a valve, *a²*, being upon each such passage to regulate the supply of gas to each kiln. The gas passes 5 into the kilns by openings *a³* and *a⁴*. In the division-walls which separate the kilns are duplex hollow spaces or flues (marked respectively *B* and *C*) communicating the one with the other by openings *b*, which openings are 10 regulated or closed by dampers *c*. In the side of the flue *C* are passages *c²*, opening from the said flue just above the outlets for gas *a⁴* in the one kiln, the flue *B* being in communication by the slots *b²*, passage or flue *b³*, and slots 15 *b⁴* with the lower part of the adjacent flue. A duplex passage consisting of flues *D* and *E* is also formed in the upper part of the walls of the kilns, the one passage, *D*, communicating by means of the openings *d* with the one 20 kiln, and the other passage, *E*, communicating by means of the openings *e* with the adjacent kiln. The said flues *D* and *E* communicate with each other by openings *d²*, which can be 25 regulated by dampers *e²*. Openings *f* are made in the roofs of the kilns, which openings are covered by slabs or dampers *f²*.

In operation, when one kiln is in fire the effluent gases produced therein are passed into the adjacent kiln through the openings *b⁴*, 30 passage *b³*, openings *b²*, passage *B*, openings *b*, and passage *C* into the adjacent kiln next in the series through the openings *c²*, and will heat the contents of the said kiln. When the first kiln has been fired off the air passes through 35 the said kiln into the adjacent kiln through the passages *B* and *C*, as before described, issuing thereinto by the openings *c²*. Gas is then turned onto this kiln, and, meeting with this hot air, burns and bakes the bricks in the said 40 kiln. The quantity of air passing through the one kiln to be heated on its passage to the adjacent kiln is regulated by the dampers *c*, and the quantity of gas admitted to this kiln is regulated by the valve *a*. When this last- 45 mentioned kiln is burned off the supply of gas is turned off therefrom, and this said kiln becomes in its turn the regenerator or heater of air for the next kiln of the series, and so on through the series, the passages marked *B²* 50 and *C²* in Figs. 1 and 4 giving communication between the respective end kilns of each row of kilns. If it is desired to admit hot air to the upper part of any kiln, this may be done by opening the dampers *f²* at the top of a fired-off kiln, and air heated by the said kiln thus 55 be caused to pass from the said kiln through the openings *d*, passage *D*, openings *d²*, and passage *E*, and into the adjacent kiln through the openings *e* to raise the temperature of the 60 upper part of the kiln or to assist in the combustion of the gas. Where cold air is to be admitted into a kiln air passes into the kiln through the flue *E*, which is open to the atmosphere at both ends. The outlet-passages 65 from each kiln and the main flues to the chimney into which these passages open are indicated in Fig. 1, and are there marked *g*.

Figs. 10, 11, 12, and 13 represent views corresponding respectively to Figs. 6, 7, 8, and 9 of a modification of my invention wherein the flues *B* and *C*, for the admission of hot air to mix and burn with the gas, are made in the brick-work outside of the kiln-walls in place of in the walls themselves. Fig. 11 is a horizontal half-section on the line 10 11, Fig. 10. Figs. 12 and 13 are transverse vertical sections taken on the line 14 15, Fig. 10, showing the opposite side walls, as indicated respectively by the arrows 12 and 13. The air from the fired-off kiln, and heated thereby, passes down by 80 the openings *b⁴* into the flue *B* through openings *b*, (one on each side,) regulated by dampers *c*, into the flue *C*, and therefrom by the slotted passages *c²* in the lower parts of the kiln-wall into the passage *a⁵*, where it mixes before passing into the kiln with the gas introduced into the said kiln through the gas-passage *a* and openings *a³*.

The flues, either in the lower part or in the upper part of the kilns, may be made single instead of duplex, the one side communicating by a number of openings with the one kiln, and with the other kiln by openings at the ends of this single flue, these said openings being regulated and closed by dampers. Single flues of 90 this construction (marked *H*) are shown in the upper part of the kiln-walls in Figs. 10, 12, and 13. The openings by which the said flue communicates with the one kiln are marked *h*, and the openings at either end of the other side of the said flue, to give communication to the other kiln, are marked *h²*, their opening being regulated by dampers *h³*. A similar arrangement may be applied at the lower part of the wall in place of the duplex flues; but I prefer the arrangements of duplex flues shown.

To give a perfect diffusion of air, it is preferred that where a continuous series of slots is employed for the passage of air into and from the various flues the said slots should break 110 bond or be placed alternately, so that the slots in one side are opposite the slot-divisions in the other side.

My invention may be applied essentially in the manner hereinbefore described to calcining-kilns, coke-ovens, or other analogous apparatus.

I claim—

1. In regenerative kilns for burning fire-bricks, pottery, or other analogous materials, and analogous apparatus, the combination of the gas-generator, the main gas-conducting passage, the passages branching therefrom to the several kilns or chambers, and the flues or passages *B* *C* for passing the heat from one 125 kiln or chamber into another adjacent kiln or chamber, as hereinbefore described.

2. In regenerative kilns and analogous apparatus, the arrangement of flues *B* *C* *b³*, openings *b⁴* *b²* *b* *c²*, and dampers *c* for giving communication from kiln to kiln or chamber to chamber, as shown and described.

3. In regenerative kilns and analogous apparatus, the arrangement of flues *B* *C*, dampers

c, and openings *b*⁴, *b*, and *c*³ for giving communication from kiln to kiln or chamber to chamber, as shown and described.

4. In regenerative kilns or chambers and analogous apparatus, the combination of the flues *B* *C*, dampers *c*, and openings *b*⁴, *b*, and *c*³ with a flue or chamber, *a*⁵, in which the air heated by the regenerated heat of a kiln or chamber is mixed with the gas about to enter another kiln or chamber to be burned therein, as hereinbefore shown and described.

5. In regenerative kilns or chambers for burning brick, and in analogous apparatus, the flues *D* and *E* and openings *d* *d*² *e*, and dampers *e*² in the upper parts of the communicating walls of the kilns or chambers, Figs. 6 to 9, and also the flue *H*, openings *h* *h*², and dampers *h*³, whether employed to admit cold or hot air to the upper part of the kiln or chamber or to admit the heat from one kiln to another at the lower part thereof, as described with reference to the upper wall of a kiln.

6. The combination of parts constituting the improved regenerative kilns or chambers or analogous apparatus, consisting of the kilns 25 communicating with each other by regenerative passages *B* *C*, (or passages *H*.) and provided with passages *a* *a*' and regulating-valves *a*², for supplying gas to be burned in the said kilns or chambers, in conjunction with the hot 30 air admitted by the passages *B*. *C*, (or passage *H*.) as hereinbefore described, and illustrated in the accompanying drawings.

In testimony whereof I have signed my name to this specification in the presence of two sub- 35 scribing witnesses.

JAMES DUNNACHIE. [L. S.]
